TOY TRUCK WITH MOVABLE CANNON OR THE LIKE

Jerrold J. Krumholz, West Orange, and Herbert Happe
Van Reisgen, Westfield, N.J., assignors to Victor
Comptometer Corporation, Chicago, Ill.

Filed Jan. 22, 1973, Ser. No. 325,665

Term of patent 14 years

Int. Cl. D21—01

U.S. Cl. D34—15 AJ

Fig. 1

Fig. 2

Fig. 3

Fig. 4

Fig. 5

FIG. 1 is a perspective view of a toy truck with movable cannon sharing our new design;

FIG. 2 is a top plan view thereof;

FIG. 3 is a rear elevational view thereof;

FIG. 4 is a side elevational view thereof; and

FIG. 5 is a front, elevational view thereof.

We claim:

The ornamental design for a toy truck with movable cannon or the like, as shown and described.
